UNITED STATES PATENT OFFICE

169,115

LIQUID-DISPENSING CLEANING UNIT FOR
TOILET BOWLS, URINALS, OR THE LIKE

Wesley Turner, Portland, Oreg.

Application May 10, 1952, Serial No. 19,657

Term of patent 14 years

(Cl. D9—2)

To all whom it may concern:

Be it known that I, Wesley Turner, a citizen of the United States of America, residing at Portland, in the county of Multnomah and State of Oregon, have invented a new, original, and ornamental Design for a Liquid-Dispensing Cleaning Unit for Toilet Bowls, Urinals or the like, of which the following is a specification, reference being had to the accompanying drawing, forming a part thereof.

In the drawing:

The figure is a perspective view of a liquid-dispensing cleaning unit for toilet bowls, urinals or the like, illustrating my new design, the bottom of the applicator being plain and the side not shown in the drawing being like the side shown therein.

I claim:

The ornamental design for a liquid-dispensing cleaning unit for toilet bowls, urinals or the like, as shown and described.

WESLEY TURNER.
